The ornamental design for a X-shaped dual shoulder strap for a golf bag, as shown, and described.

CLAIM

DESCRIPTION

FIG. 1 is a perspective view of an X-shaped shoulder strap for a golf bag showing my design;

FIG. 2 is a top plan view thereof;

FIG. 3 is a front elevation view thereof;

FIG. 4 is a side elevation view, the opposite side being a mirror image thereof; and,

FIG. 5 is a rear elevation view thereof.

The image showing the golf bag in FIG. 1 is for illustrative purposes only and forms no part of the claimed design.
